UNITED STATES PATENT OFFICE.

MARY E. GILBRETH, OF BOSTON, MASSACHUSETTS.

DESIGN FOR A SPOON.

SPECIFICATION forming part of Design No. 21,225, dated December 8, 1891.

Application filed September 21, 1891. Serial No. 406,407. Term of patent 3½ years.

To all whom it may concern:

Be it known that I, MARY E. GILBRETH, a citizen of the United States, residing at Boston, in the county of Suffolk, State of Massachusetts, have invented a new and original Design for Spoons, of which the following is a specification, reference being had to the accompanying drawings, forming part thereof.

Figure 1 is a front view, and Fig. 2 a rear view, of my newly-designed spoon.

The leading feature of my design is the figure of Cupid resting on the extremity of an arrow leading to and its point piercing a spoon-bowl shaped somewhat like a heart.

The bowl *a* of the spoon is pierced by and has

extended from it the shaft of an arrow *b*, supporting at its extreme end a conventional figure *c* of Cupid, the said figure forming the enlarged end of the handle. The arrow is shown as tufted, as at *d*. 20

I claim—

The design for a spoon, as herein shown and described.

In testimony whereof I have signed my name to this specification in the presence of 25 two subscribing witnesses.

MARY E. GILBRETH.

Witnesses:

FREDERICK L. EMERY,
EMMA J. BENNETT.
